(57) **CLAIM**

The ornamental design for a watch, as shown and described.

DESCRIPTION

FIG. 1 is a front right perspective view of a watch showing our new design;

FIG. 2 is a front elevated view thereof;

FIG. 3 is a back elevated view thereof;

FIG. 4 is a left side view thereof;

FIG. 5 is a right side view thereof;

FIG. 6 is a top view thereof; and,

FIG. 7 is a bottom view thereof.

The broken line showing of the watch band is included for the purpose of illustrating the environmental structure and forms no part of the claimed design.

1 Claim, 5 Drawing Sheets(56)
